UNITED STATES PATENT OFFICE

RALPH A. LIGHT, OF CYNWYD, AND JOSEPH W. PRICE, JR., OF PHILADELPHIA, PENNSYLVANIA, ASSIGNORS TO THE UNITED STATES METALLIC PACKING COMPANY, OF PHILADELPHIA, PENNSYLVANIA, A CORPORATION OF PENNSYLVANIA

AUTOMATIC AIR VALVE FOR SAND TRAPS

Application filed April 11, 1931, Serial No. 529,462, and in Canada May 21, 1931.

Our invention relates to sanding mechanism such as is used in connection with locomotives and is intended for use in connection with sand traps provided with air nozzles, one directed into the trap and operating to deliver sand from the trap into the delivery pipe and the other directed into the delivery pipe and operating to expel a blast of air which will clean the delivery pipe of obstructions which may have accumulated in it. The object of our invention is to provide an automatic air control valve operable by the admission of pressure air from the supply pipe of the system and operating in normal position, that is, when no pressure air is flowing to the trap, to cut off all communication between the air supply pipe and the pipes leading from the valve to the delivery and cleaner nozzles of the trap, and operating when air is admitted to the valve to first connect the air supply pipe with an outlet passage leading to the cleaner nozzle, then to close this connection and open the connection between the inlet pipe and the outlet port leading to the sand delivery nozzle. The purpose of this invention is to secure very shortly after the admission of air to the valve a short blast of full pressure air through the cleaner nozzle followed by a continuous delivery of air to the delivery nozzle and also when the supply of air under pressure is cut off to close the connection between the nozzles of the trap and the valve chamber. Further objects and features of our invention will be explained in connection with the drawings, which illustrate a preferred construction of our automatic air delivery valve and is intended for use in connection with a sander system such as is shown for instance in our application, Serial No. 460,854, filed June 13, 1930.

In the drawings,

Figure 1 is a top view of our automatic valve.

Figure 2 is a section on the line 2-2 of Fig. 1, and

Figure 3 is a section on the line 3-3 of Fig. 1.

A is a cylindrical chamber, closed at both ends by heads indicated at B and C and di-

vided by a movable wall, shown as a piston head G¹ into a valve chamber A¹ and a separate air containing chamber indicated at A². Into the valve chamber A¹ leads an admission port indicated at D, which is connected with the usual air supply pipe for air under pressure, indicated at D¹. This port D is shown as longitudinally elongated where it passes through the inner wall of the cylinder, as indicated at D², so as to maintain registry with the air groove of the cylindrical valve working in the cylinder and to be described. Provision for the delivery of air from this chamber is made by ports indicated at F, F¹, located on opposite sides of the cylindrical valve casing and radially disposed with regard to the port leading to the sand delivery nozzles at angles of 90° thereto. These ports F, F¹ are connectible to the cleaner nozzles of a pair of sand traps and the construction and disposition of these ports in connection with ports connectible with the delivery nozzles of the traps is such as to provide for a convenient arrangement of the pipes leading to the traps.

At a different, and, as shown, a lower level there is formed through the wall of the valve chamber an outlet port indicated at E, which, as shown, and where, as is usually the case, the valve is to be connected to a pair of sand traps, is preferably made of a single port formed through the inner wall of the valve casing cylinder, said port connecting with bifurcated passages indicated at E¹ E² to which separate air pipes can be attached leading to the sand delivery nozzles of two traps. G is a piston valve fitting in the cylindrical valve casing A and having as shown a head G¹ which forms a movable wall for the air containing chamber A² separating it from the valve chamber A¹. The body of the piston valve is circumferentially grooved as indicated at G², said groove being so located and shaped that it will remain in registry with the air inlet port D in all positions of the valve, that it will be out of registry with all of the air delivery ports when the valve is in normally retracted position and that as the valve is actuated it will first register with and then pass out of

registry with the air delivery ports F and F¹, thus opening these ports for a brief period and will then register with and remain in registry with the port E so that in the final position assumed by the moving valve this port will remain continuously open. An air passage, preferably of restricted area, must be provided to deliver air to the air containing chamber A² when air is admitted to the inlet port and such a passage may conveniently be made through the piston valve between the groove G² and the chamber A². Such a passage is indicated at H. I indicates a spring seated on the lower head of the casing and pressing against the lower end of the piston valve.

The normal inoperative position of the valve is that indicated in the drawings, the valve being held in this position by the spring I and the valve in this position while permitting the entrance of air to the groove G² closes all of the outlet ports in the valve chamber A¹. When pressure air is admitted through the inlet port D it passes freely into the groove G² in the valve and passes thence through the restricted air passage H to the chamber A², building up pressure in this chamber, which, acting on the piston head G¹, will, when it attains sufficient pressure, overcome the pressure of the spring I, holding the valve in non-operative position and move the piston valve G downward so as to bring the groove G² first into registry with the cleaner ports F and F¹, delivering a full head of pressure air through these ports for a brief interval, the further downward movement of the valve closing these ports bringing its groove into registry with the delivery port E, so that thereafter all of the air passing through the valve is delivered to the sand delivery nozzles. When the supply of air under pressure is cut off the air in the chamber A² will escape through the passage H and the release of pressure on the movable wall piston will then permit the spring I to restore the valve to normal inoperative position.

It will be seen that by the use of our valve we provide for the delivery of all the air coming from the high pressure supply pipe to the outlet ports leading to the cleaner nozzles at high pressure for a brief interval of time and then for the cutting off of air to these cleaner ports and the delivery of all the air thereafter through the ports connected to the sand delivery nozzles. It will also be obvious that by our construction the valve in normal inoperative position closes all connection with the outlet ports and thus prevents the passage of any particles of sand or dust into the valve casing.

Another advantageous feature of our construction is that if the valve on admission of air does not for any reason operate no air

will be lost, as both outlet ports will remain closed.

Having now described our invention, what we claim as new and desire to secure by Letters Patent, is:

1. An automatic air distributing valve adapted to be located in the air pipe system leading from a source of air under pressure to a sand trap having air delivery nozzles, one leading into the trap to effect the delivery of sand therefrom and the other directed into the delivery pipe leading from the sand trap, said automatic valve comprising in combination an air chamber having a movable wall connected to receive pressure air when air under pressure is delivered to the valve, a valve casing having an inlet port connectible to the air supply pipe of the sander system and air outlet ports connectible respectively with the cleaner and delivery nozzles of a sand trap, valve mechanism located in said casing normally closing all connection between the inlet and outlet ports and shiftable in the casing to progressively open and close the cleaner port and then to open the delivery port, resilient means operating to normally hold the valve mechanism in position to close the delivery ports and a connection between the valve mechanism and the movable wall of the air chamber whereby when pressure air is admitted to said chamber the valve is progressively shifted to progressively open and close the cleaner port and then to open the sand delivery ports.

2. In an automatic air controlled valve as called for in claim 1, the construction of the valve mechanism as a piston valve working in the valve casing chamber and grooved to maintain communication with the inlet port in all positions of the valve, said groove being so formed that on the movement of the piston valve it communicates for a portion of the movement of the valve with the outlet port leading to the cleaner nozzle and then with the outlet port leading to the sand delivery nozzle.

3. In an automatic air control valve as called for in claim 1, a piston valve having a cylindrical head which forms the movable wall of the air chamber and the cylindrical body fitting in the valve casing, said cylindrical valve being formed with a groove so shaped as to maintain communication with the inlet port in all positions of the valve, and as the valve is moved to progressively open and close the air port leading to the cleaner nozzle of the trap and then to open the air port leading to the sand delivery nozzle of the trap.

4. In an automatic air control valve as called for in claim 1, a piston valve having a cylindrical head which forms the movable wall of the air chamber and the cylindrical body fitting in the valve casing, said cylindri-

cal valve being formed with a groove so shaped as to maintain communication with the inlet port in all positions of the valve and as the valve is moved to progressively open and close the air port leading to the cleaner nozzle of the trap and then to open the air port leading to the sand delivery nozzle of the trap, said piston valve having a restricted air passage formed in it connecting the groove with the air chamber.

5. An automatic air distributing valve adapted to be located in the air pipe system leading from a source of air under pressure to a sand trap having air delivery nozzles, one leading into the trap to effect the delivery of sand therefrom and the other directed into the delivery pipe leading from the sand trap, said valve comprising in combination a cylindrical casing divided into an 15 air chamber and a valve chamber by a movable wall, said valve chamber having an inlet port leading into it, two outlet ports adapted to be connected to the cleaner nozzles of two traps and located on opposite 20 sides of the valve casing, a bifurcated outlet port connectible with delivery nozzles of two traps and located at a point in the valve casing approximately midway between the outlet ports before mentioned, a piston valve 25 working in the cylindrical casing provided with a groove so formed as to maintain communication with the inlet port in all positions of the valve, to close all outlet ports when the valve is in normal inoperative position, to progressively open and close the 30 outlet ports connectible with the cleaning nozzles as the valve moves from normal position and then to open the bifurcated outlet port connectible with the distributing 35 nozzles, a movable wall separating the air transmitting and air containing chambers operatively connected with the piston valve, an air conduit whereby air is admitted to the air chamber when pressure air is delivered 40 to the admission port of the valve casing and means operating to restore the valve and movable wall to normal inoperative position 45 when pressure fluid is cut off from the valve casing.
